UNITED STATES PATENT OFFICE.

HENRY C. SERGEANT, OF NEW YORK, N. Y.

DIRECT-ACTING ENGINE.

SPECIFICATION forming part of Letters Patent No. 355,348, dated January 4, 1887.

Application filed October 16, 1886. Serial No. 216,411. (No model.)

To all whom it may concern:

Be it known that I, HENRY C. SERGEANT, of the city and county of New York, in the State of New York, have invented a new and useful Improvement in Direct-Acting Engines, of which the following is a specification.

My invention relates to that class of direct-acting engines which are more particularly intended for rock-drills, and in each of which is employed a main valve moving as a piston within a valve-chest, and which is operated or moved alternately in opposite directions by pressure upon its end. In this class of engines, as most commonly constructed, the opposite ends of the main-valve chest are alternately placed in communication with the exhaust, so that the pressure upon the opposite end of the valve will throw or operate it. The main piston is in some cases provided with annular grooves, which serve to establish communication between the main exhaust port and passages leading from the ends of the valve-chest, and in other cases the piston has by its movement served to operate independent supplemental valves at each end of the main-valve chest, so as to simultaneously place one end of the valve-chest in communication with the exhaust and the other end of the valve-chest in communication with the steam-supply. Engines of this class, as heretofore constructed, although they may have been effective for a special class of work for which they were designed, either as heading-drills or drills for quarry work, have not in many cases operated with the best results when applied to a class of work for which they were not intended.

An important object of my invention is to provide a drill in which the valve is so constructed and operated that the drill will operate effectively upon any class of work—that is, whether employed as a heading-drill in tunnels or in outside work, as in quarries.

One feature of my invention consists in the combination, with a cylinder and a piston having reversely-arranged inclines or shoulders, and a main valve arranged to move by pressure upon its end, of a supplemental valve which is actuated by the inclines or projections on the pistons to serve the sole purpose of placing the ends of the main-valve chest alternately in communication with the ex-

haust, whereupon the valve will be moved by the pressure in the opposite end of the chest.

The invention also consists in the combination, with a cylinder and a piston having reversely-arranged inclines or shoulders, and a main valve arranged to move by pressure upon its end, of a single supplementary valve which controls the operation of the main valve, and which is moved in opposite directions alternately by the inclines or shoulders on the piston. In the above combination I prefer to make the supplemental valve in the form of an arc-shaped slide-valve, which is fitted to a corresponding seat, and which has ports or passages in its flat side or face, so that the valve will always work tight by reason of the pressure of steam or air within the cylinder, keeping it seated. I also prefer to introduce between the valve-chest and the cylinder a removable or renewable bed, which has a projection fitting within a cavity or opening within the cylinder, and which has formed in such projection the arc-shaped valve seat, in which the sliding valve works, as hereinafter described.

In the accompanying drawings, Figure 1 is a longitudinal section upon the plane indicated by the dotted line $z z$, Fig. 2, of such portions of a rock-drill as are necessary to illustrate my invention. Fig. 2 is a transverse section upon the plane of the dotted line xx , Fig. 1. Fig. 3 is a plan view with the valve-chest removed; and Fig. 4 is a horizontal section upon the plane of the dotted line yy , Fig. 1.

Similar letters of reference designate corresponding parts in the several figures.

A designates the cylinder, in which is fitted the piston B, and from the piston B extends the piston-rod B', which works through the lower cylinder-head, and has the drill or bit secured to it in a well-understood manner.

C designates the main-valve chest, in which is the main valve D; and E designates a supplemental valve, whereby the movements of the main valve are controlled, and whereby, in this example of my invention, the ends of the valve-chest C are alternately placed in communication with the main exhaust.

In this example of my invention I have illustrated a renewable or removable bed or plate, F, as introduced between the valve-chest D and the flat surface or face b , provided upon

the cylinder, and this renewable bed F has a projection, F', which enters and fits loosely in a corresponding cavity or opening, b', formed in the cylinder.

- 5 The valve here represented is of the piston type, and serves to alternately place the main ports or passages b² b³ in communication with the steam-supply and with the main exhaust port or passage b⁴. The main steam and exhaust passages b² b³ are curved laterally or carried around the cavity or recess b' in the cylinder which receives the block or projection F', as shown in Fig. 3, and are continued through the renewable or removable bed F, and the main exhaust port b⁴ is also continued through the bed F and communicates with the exhaust space or cavity b⁵, as shown in Fig. 2, and from which may lead the exhaust-pipe socket b⁶.
- 10 20 The steam-chest or valve-chest C has in opposite sides pipe-sockets c, with either of which the steam-pipe may communicate, and the other of which is closed by a plug, c'. By the movement of the main valve D in one or other direction the port or passage b² or b³ will be placed in communication with the main steam-supply, while the other port, b³ or b², will be placed in communication with the main exhaust b⁴ b⁵.
- 15 30 As here represented, the supplemental valve E is of arc-shaped form; or, in other words, it constitutes a segment of a ring, and it is fitted within a slideway or seat, d, of corresponding form in the projection F' upon the renewable bed or plate F. An important advantage of this construction is, that when the valve E and its seat become worn so as not to properly fulfill their functions, the valve and its seat may be readily renewed by removing from the machine the bed or base plate F, with its projection F', and substituting a new one. This may be done at small expense and without removing the drill from the place where it is worked to the repair-shop.
- 25 40 45 The valve E is slightly greater in length than its arc-shaped seat d, and consequently one or other end of said valve will project within the bore of the cylinder and in the path of the inclines or shoulders e e', with which the piston B is provided, as best shown in Fig. 1. If the piston be moved toward the left hand of Fig. 1 from the position there shown, its incline or shoulder e' will come in contact with the right-hand end of the valve E, and will slide said valve toward the left; but the distance between the inclines or shoulders must be such that the incline or shoulder e will pass the left-hand end of the valve in the described movement of the piston before the incline or shoulder e' comes against the right-hand end of the valve to throw it toward the left. In the valve E is a recess or cavity, e², which serves to alternately place the ports or passages f f' in communication with the port or passage f². In this example of my invention, where the supplemental valve E serves to place the ends of the valve-chest C alternately

in communication with the main exhaust, the port or passage f² leads directly to the main exhaust port and cavity b⁴ b⁵, and the passages f f' are in constant communication with the steam-passages f³ f⁴, which are formed in the valve-chest C, and which lead to opposite ends thereof. I prefer to form the recess or cove e² of the valve E in the side or flat face of said valve, as the pressure which is within the cylinder will then serve to keep the valve E pressed tightly to its seat d, and will prevent leakage.

50 55 60 65 70 75 80 85 90 95 100 105 110 115 120 125 130 In the position of parts shown in Fig. 1, the supplemental valve E is in such position that by its cove or cavity e² the passage f' is in communication with the passage f², and consequently the right-hand end of the valve-chest C is in free communication through said passages with the main exhaust. The supplemental valve E has been previously set in the position described by the movement of the piston B toward the right hand of Fig. 1, and by the action of the incline or shoulder e upon the left-hand end of the valve E. As soon as the right-hand end of the valve-chest C was placed in communication through the passages f' f² with the main exhaust the pressure which had accumulated in the left-hand end of the chest C by the slight leakage past the valve D served to throw the valve toward the right and to the position shown. The piston B, as shown, is at the extreme right-hand end of its movement, and in the position of the valve D shown the passage b² is in free communication with the main exhaust port or passage b⁴, while the passage b³ is open to steam-supply in order to admit steam to the right-hand end of the cylinder A. As the piston 100 105 110 115 120 125 130 comes near the end of its working stroke, the incline or shoulder e' acts upon the right-hand end of the valve E, and by moving it places the passages f f' in communication through the cavity or cove e² of the valve. By such movement of the valve the left-hand end of the valve-chest C is placed in free communication with the main exhaust, and the left-hand end of the valve D being relieved of pressure, said valve is moved toward the left hand of Fig. 1 by the pressure upon its opposite end, and thereby places the passage b³ in communication with the exhaust b⁴, and admits the live motive agent through the passage b² to make the return movement of the piston.

It will be observed that the supplemental valve which I have above described is very simple in its construction, and will work tight notwithstanding the wear to which it may be subjected. It may also be renewed at small cost when, by long-continued wear, such renewal is made desirable.

What I claim as my invention, and desire to secure by Letters Patent, is—

1. The combination, with a cylinder, a piston having reversely-arranged inclines or shoulders, and a main valve arranged to move by pressure upon its end, of a supplemental

valve which is actuated by the inclines or projections of the piston to serve the sole purpose of placing the ends of the main-valve chest alternately in communication with the exhaust, whereupon the valve will be moved by the pressure in the opposite end of the chest, substantially as herein described.

2. The combination, with a cylinder, a piston having reversely-arranged inclines or shoulders, and a main valve arranged to move by pressure upon its end, of a supplemental valve which controls the operation of the main valve, and which is moved in opposite directions alternately by the inclines or shoulders on the piston, substantially as herein described.

3. The combination, with the main cylinder, a piston having reversely-arranged inclines or shoulders, and a main valve arranged to move by pressure upon its end, of a supplemental arc-shaped slide-valve fitted to a corresponding seat and arranged to be moved in opposite directions alternately by the inclines or shoulders of the piston to control the operation of the main valve, substantially as herein described.

4. The combination, with the main cylinder, a piston having reversely-arranged inclines or shoulders, and a main valve arranged to move by pressure upon its end, of a supplemental arc-shaped valve fitted to a corresponding seat arranged to be moved in opposite directions alternately by the inclines or shoulders of the piston, and having a port or cavity in its flat side or face for controlling the operation of the main valve, substantially as herein described.

5. The combination, with the cylinder A, having a cavity or opening, b', the piston B, having inclines or shoulders e'e', and the main-valve chest and its valve D, of the renewable bed F for the valve-chest, provided with the projection F', having formed therein the arc-shaped valve-seat d and ports f'f'', and the arc-shaped supplemental valve E, fitting said seat and arranged to be moved by the inclines or shoulders on the piston, substantially as herein described.

HENRY C. SERGEANT.
